UNITED STATES PATENT OFFICE.

BENJAMIN F. BAIN, OF PITTSBURGH, PENNSYLVANIA.

APPARATUS FOR DEMONSTRATING TOYS.

1,162,546.

Specification of Letters Patent. Patented Nov. 30, 1915.

Application filed June 28, 1915. Serial No. 36,803.

To all whom it may concern:

Be it known that I, BENJAMIN F. BAIN, a resident of Pittsburgh, in the county of Allegheny and State of Pennsylvania, have 5 invented a new and useful Improvement in Apparatus for Demonstrating Toys, of which the following is a specification.

This invention relates to display apparatus, and particularly to apparatus for 10 playing and operating toys.

The object of the invention is to provide apparatus of this kind for displaying in operation toys operated by sand, fine shot, marbles or other similar operating material, 15 and which apparatus may be used in show windows or department stores or on the demonstrating tables in the sales department thereof.

A further object of the invention is to 20 provide apparatus of this kind which requires no attention on the part of the operator but will maintain the toy or toys in operation over an extended period, thereby enabling the salesman to give his full attention to purchasers.

The invention comprises the apparatus hereinafter described and claimed.

In the drawings, which represent one embodiment of the invention, Figure 1 is a 30 front view; Fig. 2 is a rear view with the casing open to expose the operating mechanism; Fig. 2^a is an end view of the casing, the toys being omitted; Fig. 3 is a detail sectional elevation on the line 3—3, Fig. 1; Fig. 4 is a similar view on the line 4—4, Fig. 2; Figs. 5 and 6 are cross sectional views on the lines 5—5 and 6—6, Fig. 2; and Fig. 7 is a detail plan view of the runway for the marble toy.

Referring to the drawings, the apparatus illustrated comprises a suitable cabinet or casing 1 having an upright portion 2 and an outwardly extending bottom portion or base 3 providing a flat floor 4 to receive the 45 toy or toys to be demonstrated. These toys may be of any suitable description operated by finely divided material, such as sand or fine shot, or by balls, marbles or the like. In the drawings, one toy, marked 5, is a so-called sand toy of the general form shown in the prior patents to Mahan and Moran, 911,602, February 9, 1909, and Martin and Wallace, 995,546, June 20, 1911, but may be like that shown in my prior application 50 for mechanical toy, Serial No. 2,556, filed January 16, 1915, or any other sand operated

toy, while the other toy, marked 6, is of the form shown in my prior patent for toy, No. 1,113,945, dated October 20, 1914.

The sand toy 5 embodies a hopper 7 containing a supply of sand, fine shot or other similar material which is delivered automatically by a gate or valve 8 into a car or receptacle 9 connected to a counterweight 10, said car traveling up and down an inclined track 11 and delivering into a receiver 12 at its bottom. The marble operated toy 6 comprises a trough 13 arranged to receive and hold a row of balls or marbles 14 which are delivered automatically one by one into 70 a car or receiver 15 connected to a counterweight 16, said car traveling up and down between the vertical ways 17 and discharging its marbles one by one into a receiver 18 at the bottom of said ways. In both of 75 these toys, to wit, the sand toy and the marble toy, each individual load, that is, a charge of sand or a single marble, when deposited in the movable car or receptacle produces a complete cycle of movements there- 80 of. In other words, the individual load moves the car downwardly to its lower limit of travel and simultaneously lifts the counterweight and stores sufficient power 85 therein to return the car to initial position when the individual load is discharged therefrom at the lower level. Since the specific 90 form of these toys forms no part of the present invention no further description thereof is necessary.

The casing 1 incloses the mechanism for restoring the finely divided material and marbles utilized by the two toys to the hoppers or containers at the upper ends of said toys from which said material or marbles 95 are delivered to the cars of the toys. This mechanism embodies two endless belt conveyors 19, 20 provided with buckets 21, one of said conveyors being provided for the sand toy and the other for the marble toy. The conveyor 19 travels over top and bottom pulleys 22, 23, the bottom pulley being surrounded by a casing or box 24. The receiver 12 into which the sand toy 5 discharges has a bottom outlet delivering to a 105 conduit 25 which communicates with the casing or box 24. Each bucket of the conveyor 19 dips into the sand in said casing and takes a load therefrom and as it travels over the upper pulley 22 discharges said 110 load into a bin 26, from which the sand flows through a pipe 27 extending out

through the wall of the casing 1 to a position over the hopper 7.

The marbles for operating the marble toy 6 emerge from the receiver 18 and travel 5 along a gutter 28 to an opening 29 in the floor 4 from which they travel through a tortuous runway 30 to a box or casing 31 surrounding the lower pulley 32 over which travels the conveyer 20. Above the casing 31 is

10 a hollow extension 33 of a size sufficient to hold a dozen or more marbles. As the marbles roll from the runway 30 into the casing 31 they drop in front of the moving buckets 21 of the conveyer 20. Each bucket 15 picks up a marble and if a plurality of marbles are present they are pushed upwardly and to one side in the extension 33, so that only a single marble is lifted by each bucket. These marbles are carried over 20 the top of the upper pulley 34 and are discharged into a box 35, from which they run through a trough 36 to a conduit 37 extending through the wall of the casing 1 and terminating above the trough 13.

25 The upper pulleys 22 and 34 are connected to rotate together by a sprocket chain 38, and one of said pulleys, such as the pulley 34, is provided with a sprocket 39 from which a chain 40 leads to a sprocket 30 on a short shaft 41. Said shaft is provided with a large belt wheel 42 over which passes a belt 43 from a small pulley 44 on the shaft of a driving motor, such as an electric motor 45.

35 In operating this device both toys are provided with full supplies of the operating medium, the toy 5 with the proper supply of sand or other finely divided material, and the toy 6 with a sufficient number of balls 40 or marbles. If the mechanism is stopped the sand and marbles collect in the boxes or receivers 24 and 31. When the motor is started sand and marbles are elevated by their respective conveyers and discharged 45 into their respective toys, which continue to operate in the usual manner as long as the motor is allowed to run. The apparatus therefore is of particular value for demonstrating toys in show windows of department stores, as no attention is required after the mechanism is started. It can also be used on demonstrating tables in sales departments and in any other place where it is desired to operate the toy for an extended period.

55 What I claim is:

1. Apparatus for displaying toys, comprising in combination, a toy embodying a movable member adapted to be operated 60 through one complete cycle of movement by an individual load deposited therein, a sup-

ply receptacle arranged to automatically deliver an individual load to said member at the beginning of each cycle of its movement, a receiver at a lower level into which 65 said loads are deposited by the movable member, and mechanism for transferring said loads from the receiver to the supply receptacle and maintaining a supply of loads therein. 70

2. Apparatus for displaying toys, comprising in combination, a toy embodying a reciprocating member adapted to operate back and forth through one complete cycle by depositing an individual load therein, a supply receptacle arranged to automatically deliver an individual load to said member at the beginning of each cycle of its movement, a receiver at a lower level into which 75 said loads are deposited by the member, and mechanism for transferring said loads from the receiver to the supply receptacle and maintaining a supply of loads therein. 80

3. Apparatus for displaying toys, comprising in combination, a toy embodying a reciprocating member adapted to be operated in one direction by an individual load deposited therein, a counterweight adapted to be lifted by said load for returning the member to initial position when said load is 85 released therefrom, a supply receptacle arranged to automatically deliver individual loads to said member, a receiver into which said loads are deposited by said member, and a power operated continuously acting 90 elevator for lifting the loads from the receiver to the supply receptacle and maintaining a supply of loads therein. 95

4. Apparatus for displaying toys, comprising a casing having a shelf to support a toy, an elevator within said casing, means for conducting toy operating material from the outside of said casing through the same to the elevator, and means for conducting material from said elevator to the outside 100 of the casing at a higher level than said shelf and depositing the same in said toy. 105

5. Apparatus for displaying toys, comprising a casing arranged to support a toy on the outside thereof, an elevator within 110 said casing, means for conducting operating material from said toy through the casing to the elevator, and means for conducting material from said elevator to the outside of the casing at a higher level and for delivering it to said toy. 115

In testimony whereof, I have hereunto set my hand.

BENJAMIN F. BAIN.
